[57] CLAIM

The ornamental design for an aquarium pump indicator, as shown and described.

DESCRIPTION

FIG. 1 is a front perspective view, showing the cover in a first position, of an aquarium pump indicator according to the new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a front perspective view, showing the cover in a second position, of the aquarium pump indicator shown in FIG. 1;

FIG. 9 is a front elevational view thereof with the cover in the second position;

FIG. 10 is a bottom plan view thereof with the cover in the second position;

FIG. 11 is a top plan view thereof with the cover in the second position;

FIG. 12 is a rear elevational view thereof with the cover in the second position;

FIG. 13 is a left side elevational view thereof with the cover in the second position; and,

FIG. 14 is a right side elevational view thereof with the cover in the second position.
